UNITED STATES PATENT OFFICE.

WILLIAM A. BRANDES, OF NEW YORK, N. Y.

SLED.

1,286,217.

Specification of Letters Patent.

Patented Dec. 3, 1918.

Application filed February 23, 1918. Serial No. 218,827.

To all whom it may concern:

Be it known that I, WILLIAM A. BRANDES, a citizen of the United States, residing at New York, in the county of New York and State of New York, have invented new and useful Improvements in Sleds, of which the following is a specification.

This invention relates to toys and aims to provide a novel form of sled in which the 10 rider stands in an upright position upon the platform or top of the sled and maintains his balance by means of handle bars located in advance of the platform.

The invention resides particularly in the 15 pivotal mounting of the handle bars, which permits of their being moved to an angular position enabling the user to run behind the platform until the sled has acquired the desired momentum and then jump on the 20 platform; the handle bars at the same time being swung upon their pivots to accommodate the new position of the rider.

It is also the purpose of the invention to provide either a single or a double runner 25 sled and to provide the platform of the former with a foot-engaging loop or stirrup to prevent the foot from slipping from the platform.

Other objects and advantages of the invention will appear when the foregoing description is read in connection with the accompanying drawings, in which—

Figure 1 is a perspective view of a sled constructed in accordance with the present 35 invention, a runner being shown in position behind the platform preparatory to mounting the platform;

Fig. 2 is a similar view with the rider upon the platform;

Fig. 3 is a transverse sectional view showing the pivotal mounting of the handle bars;

Fig. 4 is an enlarged fragmentary side elevation of such pivotal mounting with parts broken away; and

Fig. 5 is a perspective view of a single runner sled.

Referring to the drawings in detail and especially to the form of the invention shown in Figs. 1 and 2, the sled includes a 50 pair of spaced parallel runners 10 having their forward ends upwardly curved, as indicated at 11, and provided upon their bot-

tom edges with metallic strips or bars 12. Connected to the runners 10 at a point intermediate their lengths, is a platform 13, 55 this platform being relatively short, but of sufficient length to conveniently accommodate a person standing thereon.

Secured to each of the runners 10 in advance of the platform are rods 14, the lower 60 ends of these rods being secured in socketed members 15, by means of a pin 16. The opposite end of the members 15 is bifurcated to provide alined ears 17, which are adapted to receive between them a bearing 65 member 18, the latter being provided with a transversely disposed opening 19 for alinement with openings 20 provided in each of the ears 17. These openings receive a pivot pin 21, by means of which rods 14 are pivotally secured to the runners 10. The upper or opposite end of each of the rods 14 is rigidly secured to a transversely disposed handle bar 22, which is adapted to be 70 grasped by the rider to aid in maintaining 75 his balance upon the platform.

In the use of the sled the handle bar 22 and rods 14 are inclined rearwardly at a sufficient angle to permit the user to run behind the platform 13 for the purpose of acquiring the desired momentum. The user 80 then jumps upon the platform, the handle bar at the same time raising to accommodate itself to the new position of the user.

In the form of the invention shown in 85 Fig. 5, only one runner is employed. Mounted upon this runner is a platform or block 23 which is of sufficient dimensions to accommodate one foot of the user. A stirrup 24, which may be in the form of a strap or 90 other flexible element is secured to each side of the platform or block 23 for the purpose of receiving and holding the foot thereon. A single rod 25 is pivoted to the runner in advance of the platform, while a handle bar 95 26 is secured to the upper end of this rod as shown.

The invention is susceptible of other changes in its form and proportion, and the right is reserved to make any changes that 100 properly fall within the scope of the appended claim. For example the handle bar rods may be rigidly secured to the runners.

Having described the invention, what is claimed is:

A sled comprising spaced parallel runners, a platform secured to and connecting said runners at a point intermediate their lengths, bars having one end pivotally secured to each of said runners at a point in advance of the platform, a handle connecting the

opposite ends of said bars, said bars being of sufficient length to permit of the handle being swung rearward beyond the rear end of the platform or forward beyond the front end of the runners.

In testimony whereof I affix my signature.

WILLIAM A. BRANDES.
